ATTORNEY

UNITED STATES PATENT OFFICE

JAMES H. FRASER, OF FRANKFORT, INDIANA

SLIDING DOOR

Application filed August 30, 1929. Serial No. 389,509.

My invention relates to improvements in sliding doors and more particularly to sliding doors used on box cars and consists in the combinations, constructions, and arrangements herein described and claimed.

An object of my invention is to provide a sliding door supported at a single point for the purpose of minimizing movements thereof due to vibrations transmitted thereby through its connection with the sills or the door posts of the box car.

A further object of my invention is to provide a sliding door having a support therefor which guides said door in a straight line reciprocation on pivotal supports rather than sliding supports with consequent greater ease of operation.

A further object of my invention is to provide a sliding door of the type described which will automatically lock itself at full open and full closed positions.

A further object of my invention is to provide a sliding door of the type described, the supporting means of which may be mounted on either side of the opening forming the door way or on either the inside or outside surface of the door.

A further object of my invention is to provide a device of the type described which is simple in construction, has few parts and is not likely to get out of order easily.

Other objects and advantages will appear in the following specification and the novel features of the invention will be particularly pointed out in the appended claim.

My invention is illustrated in the drawings forming part of this application, wherein:

Figure 1 is a front elevational view of my device mounted in operative position;

Fig. 2 is a sectional view of the device on line 2—2 of Fig. 1;

Fig. 3 is a front elevational view of my device showing the door moved to a different position;

Fig. 4 is a sectional view on line 4—4 of Fig. 3;

Fig. 5 is an elevational detail view of a portion of the device with the parts in one operative position; and

Fig. 6 is an elevational detail view of a

portion of the device with parts shown in another operative position;

Fig. 7 is a sectional detail view of a portion of the device.

In carrying out my invention I make use of a door way shown at 1 of an ordinary box car. For mounting the door 2 in operating relation to this door way I provide a set of linkages comprising a long link member indicated at 3 and providing a pivotal support for the door 2 as indicated at 4. Pivotally mounted intermediate the ends of this long link 3 as indicated at 5 is a short link member 6 which is swivelly mounted adjacent the door way at the top thereof as shown at 7. A bracket member 8, providing an extension 8a, and depending flange 8b fixed adjacent said door way provides a suitable mounting means for this short link 6.

For securing a straight line reciprocatory motion of the door 2, I slidably mount the long link 3 in the slot 9 of the locking bracket 10 by means of stud 11. This stud 11 may be provided with an anti-friction roller for the purpose of insuring easy operation of said stud in said slot.

As more clearly appears in Figs. 5 and 6 the bracket member 10 is provided at the upper end of the slot 9 therein with a recess 12 adapted for the reception of the stud 11 when moved to the end of the slot 9 for a purpose presently to be described. The bracket member 10 is suitably formed so as to project from the side of the car sufficiently to allow clearance for the passage of door 2 as well as to permit the stud to freely move in said slot between the bracket and the side of the car.

For additionally guiding the door as well as sealing the top of said door against the weather, I have provided a Z-shaped guiding rail indicated at 13 and being provided with a flange 14 adapted for fastening to the side of the car, a flange 15 adapted for projecting over and guiding the door, and an intermediate portion 16 adapted for engagement with the top of said door for guiding and sealing the same. This guiding and sealing plate 13 may be made of an ordinary Z-bar.

For further guiding the door, slides 17 are provided being fastened below the lower sill of the door way to the side of the car and comprising horizontal portions 18 adapted for engagement with the bottom of the door and vertically extending flange portions 19 adapted for engagement with the front of the door for holding the same in position.

It is readily apparent that the supporting linkage with the accompanying mounting means need not be mounted exactly in the position illustrated. The mounting means could be placed on the opposite side of the door way for operation similar to the position illustrated except in the opposite direction. It is easily seen that the supporting linkages could be placed on the opposite side of the door with as effective operation as if positioned as illustrated.

From the foregoing description of the various parts of the device the operation thereof will be readily understood. This door, as has been previously stated, is designed for use on box cars, or other vehicles, buildings and similar enclosures where it is desired to secure ease of operation as well as automatic locking of the same in open or shut positions. As is readily apparent from examination of Figs. 1 and 3 the door 2 may be operated from the closed position shown in Fig. 1 to the open position shown in Fig. 3 by simply sliding the same. The door sliding in a straight line supported from the end of the link 3 as shown at 4 by a short link 6 and bracket support 8, a natural arcuate movement of the supporting end of the long link 3 being altered by means of the slidable mounting of the other end of the link 3 to a straight line reciprocatory movement in a well known manner. The stud 11 at the ends of such reciprocatory movement engages in the recess 12 as is more clearly shown in Figs. 5 and 6 and holds the links extended in door closed or door open position, while the slot 9 accommodates said stud during the movement of the door. The door being supported at one point as indicated at 4, above the center of gravity is not subject to as large a number of vibrations as found in other mounting means. The door is prevented from movement outwardly or inwardly by its engagement with the additional guiding means 17 and 13 and its engagement against the sills of the doorway.

I claim:

In combination, a sliding door, guide means therefor including an upper rail having a depending bracket, means for holding said door in open or closed positions comprising a bracket having a slot and recess, a long link pivotally connected medially of said door, a short link pivotally connected to said long link and intermediately thereof and to said depending bracket, and said long link

having a stud slidably engaged in said slot and adapted to seat in the recess thereof upon movement of said door into open or closed positions.
